UNITED STATES PATENT OFFICE.

THOMAS E. MURRAY, JR., AND JOSEPH B. MURRAY, OF BROOKLYN, NEW YORK.

HOLLOW PROJECTILE.

1,303,576.

Specification of Letters Patent.

Patented May 13, 1919.

Application filed July 15, 1918. Serial No. 244,937.

To all whom it may concern:

Be it known that we, THOMAS E. MURRAY, Jr., and JOSEPH B. MURRAY, citizens of the United States, residing at Brooklyn, in the 5 county of Kings and State of New York, have invented a certain new and useful Improvement in Hollow Projectiles, of which the following is a specification.

The invention is a hollow projectile of 10 the type thrown by trench mortars, and more especially designed to hold a lethal gas under pressure. The invention consists in the construction whereby the projectile is made of a plurality of parts, which by electrical means are rendered integral and gas 15 tight at their places of union, so that leakage of the dangerous gas is prevented.

In the accompanying drawings—

Figure 1 is a section of our shell on the 20 line 1, 1 of Fig. 2. Fig. 2 is a section on the line 2, 2 of Fig. 1. Fig. 3 is an end view of the fuse-receiving plug showing the rib to which the booster tube is electrically welded.

Similar letters of reference indicate like 25 parts.

The shell body is produced by the process which is set forth in our copending application Serial No. 244,935 filed July 15, 1918. That is to say, briefly, from a plate of thin 30 or sheet metal we produce by pressing in suitable dies, a unit section which represents one-half of the shell divided on a longitudinal plane. A plurality of these sections are all alike, and hence interchangeable, so 35 that any two of them when placed with their edges in registry will form a complete shell. Two sections A, B are shown thus placed in Fig. 1. The edges of said sections are then integrally and electrically 40 united by currents of great strength and of very brief duration, whereby the metal of one section is rendered so completely and integrally coherent with the metal of the other section as that the strength at the 45 joint is as great as if not greater than the metal elsewhere: or in other words, the shell becomes substantially of one piece, everywhere of homogeneous metal.

In shells hitherto devised for containing 50 a lethal gas under pressure and in which there are joints between the parts of the structure, much difficulty has been found in making these joints gas tight. Various expedients, such as packing said joints with 55 cement, have been tried. So also attempts

have been made to effect a satisfactory union by the blow-pipe flame, and by seating one part within another, or making one part overlap the other and then forcing them together under heavy mechanical or 60 hydraulic pressure. We are not aware that any certainly successful result has been obtained. Ordinary welding or blow-pipe welding involves the use of fluxes which remain in and more or less impair the joints; 65 so also it is never certain that the union is perfectly made, for there is always danger of burning the thin metal, or of irregular or imperfect adhesion between the contacting surfaces. So far as we are advised, no shells 70 have been yet produced competent to withstand a hydrostatic pressure of over 1200 pounds to the square inch. Furthermore, in gas shells the pressure of the gas is variable. If introduced, as is now usual, at 40 75 pounds to the square inch, it may be increased to double that amount if the shell be sufficiently heated, as may happen if exposed in the sun in summer.

It is unnecessary to explain why a gas 80 shell liable to leakage of its lethal contents is quite as dangerous to friend as to foe.

We have discovered that a shell joint electrically welded by currents of great volume and of very brief duration is absolutely impervious to gas within, and even far beyond, any utilizable limit of pressure. We have tested such joints at pressures of 4000 pounds to the square inch and under water without producing any evidence of leakage. 90 In fact in hand grenades made in two sections of thin sheet metal electrically welded together as described, we have used gas pressures sufficient to start deformation of the sections without any leakage showing itself. 95

Gas shells are usually made with a tubular projection C at one end which is threaded to receive the fuse-holding metal plug D. To this plug the booster tube E has to be united, the said tube extending into the body 100 of the shell containing the gas under pressure, and itself containing the blowing charge of explosive which after ignition by the fuse determines the rupture of the shell and the liberation of the contained gas. 105

The attachment of the tube E to the plug D has been a serious source of trouble, and it is here especially that the embedding of the end of the tube in a groove in the plug with subsequent rolling or pressing of the 110

parts together has been a preferred expedient. But we find that this also leaks gas, and is not to be depended upon.

We have met the difficulty by forming on 5 the inner face of the plug D a circular rib F to register with the open butt end of the tube E, and then electrically welding, as described, the tube end and rib together. The tube then becomes integral with the 10 plug, and as the plug is externally threaded to engage with the internally threaded projection C, tube and plug are inserted into and removed from the shell at the same time.

It is to be noted that in our construction 15 both of the critical joints, namely, between the shell sections A, B and between booster tube E and plug D, are absolutely gas tight, and that these are all the joints there are, excepting the one between the fuse plug D 20 and projection C. At this joint relative detachability of the parts is required in order that the loaded booster tube with the fuse plug may be inserted after the shell is gas charged.

25 The term "lethal gas" used in the claims means any gas which on contact with the human body or when taken into the lungs is irritating, corrosive, poisonous, or in any other way injurious to health or destructive 30 to life.

We claim:

1. A hollow projectile for containing, under pressure, a lethal gas, comprising a 35 plurality of sections electrically rendered impervious to said gas at their places of union.

2. A hollow projectile for containing under pressure a lethal gas, comprising a plurality of parts electrically and integrally

united and thereby rendered, within a selected pressure limit, gas-tight at their places of union. 40

3. A hollow projectile for containing under pressure a lethal gas, comprising a plurality of interchangeable sections of sheet 45 metal with their edges in registering contact and electrically and integrally united and thereby rendered, within a selected pressure limit, gas-tight at their joints.

4. A hollow projectile for containing gas 50 under pressure, comprising two interchangeable longitudinally divided sections of struck up sheet metal integrally and electrically welded at their registering edges, an integral tubular projection on one end of said 55 projectile, a fuse carrier in said projection, and a booster tube integrally and electrically butt-welded to the inner face of said fuse carrier.

5. A hollow projectile for containing gas 60 under pressure, comprising two interchangeable longitudinally divided sections of struck up sheet metal integrally and electrically welded at their registering edges, an integral tubular projection on one end of said 65 projectile, a fuse carrier in said projection, a circular rib integrally formed on the inner face of said carrier, and a booster tube integrally and electrically butt-welded to 70 said rib.

In testimony whereof we have affixed our signatures in presence of two witnesses.

THOMAS E. MURRAY, JR.
JOSEPH B. MURRAY.
